CARBURETOR CHOKE CONTROL DEVICE

Joseph Schweiss, St. Louis, Mo., assignor to Carter
Carburetor Corporation, St. Louis, Mo., a cor-
poration of Delaware

Application August 31, 1939, Serial No. 292,869

7 Claims. (Cl. 123—179)

This invention relates to choke control devices for internal combustion engine carburetors and more particularly to devices for conveniently opening the choke valve against the resistance of automatic choke mechanism. These devices are commonly called "unloaders."

With the object in mind of preventing the inexperienced operator from inadvertently operating the "unloading mechanism" simultaneously with the starting motor, a mis-operation which frequently occurs in arrangements having both starting switch and "unloading" device interconnected with the throttle, I have provided mechanism which will perform the "unloading" function only after a period of cranking sufficient to start an engine under normal starting conditions.

It is a further object of this invention to provide an "unloading" mechanism actuated by an electro-magnet, the control of which may be either independent of or dependent upon the throttle valve position.

Other objects and advantages will appear in the following description and accompanying drawing referring to which Fig. 1 is a somewhat diagrammatic representation of a carburetor showing one form of my invention. Shown diagrammatically therewith is a starting motor circuit and source of electrical energy.

Numerical 1 generally indicates a conventional downdraft carburetor having an air inlet 2 and a discharge outlet 3. For control of the air inlet an unbalance plate-type choke valve 4 rigidly attached to a rotatable shaft 5 is provided. Shaft 5 extends outwardly from both sides of the carburetor and on the far side extends into the automatic choke mechanism housing 6. The automatic choke mechanism includes the usual thermoreactive element 7 which yieldably positions the choke valve in accordance with the temperature in a manner described in the patent to I. E. Coffey, #2,085,351. The discharge outlet 3 is controlled by a plate-type throttle valve 8 rigidly attached to the rotatable shaft 9. Rigidly attached to the near end of choke shaft 5 is a disc-like member 10 having a radial projection 11. Adjacent member 10 and loosely mounted for rotation on shaft 5 is a lever 12 pivotally attached at one end to the armature 13 of an electro-magnet 14. At its opposite end lever 12 carries a pin 15 adapted to abut projection 11 and thereby rotate member 10 and consequently the choke valve toward an open position as armature 13 descends.

Rigidly attached to the near end of throttle

shaft 9 is an operating lever 20 having a perforation at its outer end for attachment of a rod 21 for remote manual control. A spring 22 normally urges the throttle valve toward a closed position. The cam surface 23 on lever 20 is provided to close switch 24 as the throttle is moved toward an open position. In the modification shown, electro-magnet 14 is connected with a starting motor relay switch 15 in the circuit 16 through parallel circuit 16a. The circuit for starting motor 17 is indicated at 18. Electrical energy is supplied by storage battery 19. Two switches are indicated in the starting relay circuit 16, namely, a suction operated switch 25 and the aforementioned throttle switch 24. A good form of starting device for use in the present invention and which includes an additional switch in the relay circuit controlled by generator output is shown and described in a patent to I. E. Coffey No. 2,174,313.

To provide a predetermined delay of the functioning of the unloader and thereby permit sufficient cranking with closed choke to start an engine under normal conditions I have provided a U-shaped heat responsive bi-metallic element 26 series connected in the circuit 16. A resistance coil 27 in the ground lead from element 26 has been provided for balancing. It will be understood that element 26 is so proportioned as to respond to the heat generated by the flow there-through to spread and connect parallel circuit 16a to circuit 16 after a predetermined interval during which circuit 16 is closed.

The operation of the device is as follows:

Upon starting a cold engine the choke valve 4 will be yieldably held in the position shown by heat responsive element 7. As the throttle lever is rotated clockwise to any position beyond that necessary to close switch 24, current will flow through circuit 16 thereby closing starting motor relay 15 to crank the engine. After the period required for element 26 to respond sufficiently to connect parallel circuit 16a and, if within this interval the engine has not been successfully started, electro-magnet 14 will be energized and will open choke valve 4 in a manner described. If, however, the engine has been successfully started within the interval, suction operated switch 25 will open to break the circuit 16 at that point and remain open during operation of the engine. As the engine warms up the choke valve is free to rotate counterclockwise in an opening direction independent of lever 12. I do not wish to be limited to the detailed description and structure shown, the use of all modifications

within the scope of the appended claims is contemplated.

I claim:

1. In combination, a carburetor having a choke valve, a throttle valve, mechanism for yieldably urging said choke valve toward a closed position, an electro-magnet for moving said choke valve toward an open position against the resistance of said mechanism, an electrical circuit for said electro-magnet, and means co-acting with said throttle valve for opening and closing said electrical circuit.
2. In combination, a carburetor having a choke valve, a throttle valve, mechanism for yieldably urging said choke valve toward a closed position, an electro-magnet for moving said choke valve toward an open position against the resistance of said mechanism, an electrical circuit for said electro-magnet, a switch in said circuit arranged to coact with said throttle valve, and a second switch in said circuit responsive to heat.
3. In combination, an internal combustion engine, a carburetor having a choke valve, an automatic choking device for yieldably urging said choke valve toward a closed position, an engine starting circuit, a normally disconnected branch of said circuit, an electrically operated device in said branch for moving said choke valve toward an open position against the resistance of said choking device, and a delayed action switch device, responsive to the flow of electrical current through said starting circuit for connecting said branch thereto.
4. In combination, a carburetor having a choke valve, a throttle valve, automatic choke mechanism constructed and arranged to yieldably urge said choke valve toward a closed position, a starting motor control circuit, a normally disconnected branch of said circuit, a throttle actuated switch in said starting motor control circuit, an electro-magnet in said branch for moving said choke valve toward an open position against the resistance of said automatic choke mechanism, and a heat responsive element in said start-

ing motor control circuit arranged to connect thereto said branch circuit after a predetermined interval in which said starting motor control circuit is closed.

5. In combination, a carburetor having a choke valve, an automatic choking device for urging said choke valve toward a closed position, and a manually controlled unloading device comprising an electro-magnet constructed and arranged to move said choke valve toward an open position against the resistance of said automatic choking device, an energizing circuit for said electro-magnet, a manually operated control switch in said circuit, and a delayed action switch device capable of connecting said electro-magnet into said circuit after a predetermined interval during which said manual switch is closed.

6. In combination, an internal combustion engine, an engine starting circuit, a carburetor having a choke valve, automatic mechanism for moving said choke valve toward a closed position, an electro-magnet in said circuit constructed and arranged to move said choke valve toward an open position against the resistance of said automatic mechanism under certain conditions, a manual control switch in said circuit, and automatic means functioning to maintain a broken starting circuit during operation of the engine.

7. In combination, an internal combustion engine, an engine starting circuit, a carburetor having a choke valve, an automatic choking device for yieldably urging said choke valve toward a closed position, a manual control switch in said starting circuit, an electro-magnet constructed and arranged to move said choke valve toward an open position against the resistance of said automatic choking device, a thermostatic switch in said starting circuit capable of connecting said electro-magnet in said starting circuit after a predetermined interval during which said starting circuit is closed, and automatic means functioning to maintain a broken starting circuit during operation of the engine.

JOSEPH SCHWEISS.
